CLAIM

The ornamental design for a bottle, as shown and described.

DESCRIPTION

FIG. 1 is a top perspective view of a bottle, showing our new design, with the cap portion secured.

FIG. 2 is a side view thereof.

FIG. 3 is a top view thereof.

FIG. 4 is a bottom view thereof.

FIG. 5 is an exploded side view thereof, with the cap portion unsecured; and,

FIG. 6 is a partial cross sectional view through line 6-6 in FIG. 4 of the lower end of the bottle showing the contours of a bottom surface of the bottle in some examples of the design.

The dashdot broken lines in the drawings indicate the appearance of any portion of the article between the dashdot broken lines forms no part of the claim.

The broken lines are shown for the purpose of illustrating parts of the bottle that form no part of the claim.

1 Claim, 5 Drawing Sheets(56)
